ADVERTISING CALENDAR

Joseph S. Fisher, New York, N. Y.

Application December 27, 1934, Serial No. 759,335

3 Claims. (Cl. 40—107)

This invention relates to improvements in good-will advertising articles, and more particularly to a combined advertising calendar and greeting card.

5 It has been the practice in the printing of calendars for advertising purposes to display the advertiser's message upon the front of the calendar, which is distasteful to certain class of recipients, with the result that the calendar is either thrown away by the recipient, or placed 10 in some obscure place which makes it unavailable for instant use when desired. It is therefore the main purpose of this invention to provide an advertising calendar having the twelve 15 months displayed thereon and on which a direct message in the form of a greeting or advertisement may be carried to a prospective customer of an advertiser by printing the same upon a cover sheet which is attached to the back of the 20 calendar and folded over the front thereof. The folded sheet is detachable from a stub attached to the back of the calendar by tearing the same upon a weakened line, there being an advertisement printed on the remaining stub to which the 25 recipient of the calendar may refer at all times. By this arrangement, the front face of the calendar may be left free of advertising matter and the same set up upon a desk or hung upon the wall as a useful and decorative article.

30 Another feature of the invention is to provide an advertising article in which the advertising matter is printed on a cover sheet which is attached to the rear of a calendar, a portion of the sheet carrying the advertisement remaining attached to the back of the calendar after the cover 35 portion thereof is torn away. This enables the use of a standard design calendar which may be kept in stock by the printer or manufacturer and the cover sheets printed up to suit the advertising copy of different advertisers as orders for the 40 calendars are placed.

A further object resides in a combined advertising calendar and greeting card which is simple of construction, inexpensive of manufacture, and which is free of direct display of advertising when in use upon the recipient's desk or hung upon the wall so as not to detract from the decorative furnishings of a room.

Other objects of the invention will appear as 45 the following specification is read in conjunction with the accompanying drawing, in which,

Figure 1 is a perspective view of my combined calendar and greeting card, showing one corner of the cover sheet turned back.

50 Figure 2 is a rear elevational view.

Figure 3 is a side elevational view of the article in a set up position.

Figure 4 is an enlarged detail vertical sectional view on the line 4—4 of Figure 2.

Figure 5 is a fragmentary perspective view illustrating the manner in which the cover sheet is torn free of the calendar.

Referring to the drawing by reference characters, the numeral 10 designates a flat rectangular shaped body which may be constructed of cardboard or other similar stiff material, the front face of which contains a calendar 11 of the twelve months of the year. Adhesively secured to the rear side of the body 10 centrally thereof is an easel which includes a pair of foldable 10 props 13—13 normally disposed flat against the back of the body as shown in Figure 2 of the drawing, but which may be swung to a position at right angle to the body as shown in Figure 3, and held in such position by a locking brace flap 15 15 20 14. The flap 14 also lies flat against the rear of the body 10 when in folded position, but extends outwardly therefrom when in operative position.

Associated with the calendar 10 is a detachable greeting card which includes a flexible sheet of 25 paper 15 of a width equal to the width of the body 10 but being of a height greater than the body 10 for a purpose to be hereinafter appreciated. The sheet of paper 15 is provided with a weakened tear-line 16 adjacent its top edge and 30 parallel to the said top edge. The weakened line 16 divides the sheet into an attaching stub section 17 and a cover section 18. The stub section 17 is adhesively secured to the back of the body 10 adjacent the top edge of the said body in a 35 manner so that the weakened tear-line 16 is disposed inwardly or below the top edge of the body 10. The cover section 18 is folded over the top of the body 10 to lie flat over the front face 40 of the said body to protect the calendar 11 until placed in use.

Printed on the cover section 18 may be a message of greeting 19 or other desired printed matter, while printed on the stub section 17 may be an advertisement 20 of the sender of the calendar. It will be appreciated that the printed matter is applied to the sheet 15 prior to its attachment to the body 10 and when printing, the printed matter 19 is in reversed relation with respect to the printed matter 20 so as to be read 45 50 from opposite sides of the article without turning the same upside down.

In practice, the article may be used in good-will advertising, the name of the advertiser appearing on the stub 17 and upon the cover section 55

18 so that the recipient of the article will know the source from which it came. It should be borne in mind that no advertising matter appears on the face of the body 10, thus after 5 receiving one of the articles, the recipient thereof may tear the cover section 18 free of the stub section 17, as shown in Figure 5 of the drawing. By disposing the tear-line 16 below the top edge of the body 10, the stub 17 is invisible from the 10 front, but the owner is aware of the name and address appearing on the stub section for reference thereto when needed. By bending out the flaps 13 and 14 of the easel 12 to the position shown in Figure 3, the article may be set in an 15 upright position upon the desk and provide an attractive article free of the display of an advertisement. In the event that it should be desired to hang the calendar upon the wall, a tab 21 20 extends upwardly from the easel 12 in which an opening 22 is provided for receiving a nail, hook or other like support.

While I have shown and described what I consider to be the preferred embodiment of my invention, I wish it to be understood that such 25 changes as come within the scope of the appended claims may be resorted to if desired.

Having thus described the invention, what I claim as new and desire to secure by Letters Patent of the United States, is:—

30. 1. A combined calendar and greeting card comprising a flat body having the calendar months of the year on the front side thereof, a greeting card including a flexible sheet, a weakened line extending across said sheet adjacent the top edge thereof and parallel thereto, said weakened line dividing the sheet into a cover section and a stub section, said stub section being

adhesively secured to the back of said body adjacent the top thereof while said cover section is folded over the top edge and front of said body to lie flat thereagainst.

2. A combined advertising calendar and greeting card comprising a flat rectangular shaped body having a calendar on the front face side thereof, a flexible rectangular sheet, a weakened line extending across said sheet adjacent the top edge thereof and parallel thereto, said weakened line dividing the sheet into a relatively narrow attaching stub section and a cover section, said stub section being adhesively secured to the rear of said body adjacent the top thereof so that the weakened line is parallel to but below the top 15 edge of said body, said cover section being folded over the top edge and front of said body to lie flat thereagainst.

3. A combined advertising calendar and greeting card comprising a flat rectangular shaped body having a calendar on the front face side thereof, a flexible rectangular sheet, a weakened line extending across said sheet adjacent the top edge thereof and parallel thereto, said weakened line dividing the sheet into a relatively narrow 20 attaching stub section and a cover section, said stub section being adhesively secured to the rear of said body adjacent the top thereof so that the weakened line is parallel to but below the top edge 25 of said body, said cover section being folded over the top edge and front of said body to lie flat thereagainst, printed matter contained on the outer side of said cover section and stub section, the printed matter on the respective sections being reversed with respect to each other.

JOSEPH S. FISHER.
